UNITED STATES PATENT OFFICE.

SVEND FÆRCH, OF GREJSDAL PR. VEJLE, DENMARK, ASSIGNOR TO HIMSELF AND
BRÖDR. BRINCKER, GREJSDAL HAMMERVAERK, OF VEJLE, DENMARK, A FIRM OF
DENMARK.

STAY-ROPE TIGHTENER WITH TURNBUCKLE THEREFOR.

Application filed November 27, 1922. Serial No. 603,988.

To all whom it may concern:

Be it known that I, SVEND FÆRCH, subject of the King of Denmark, residing at Grejsdal pr. Vejle, Denmark, have invented certain new and useful Improvements in Stay-Rope Tighteners with Turnbuckles Therefor, of which the following is a specification.

The present invention relates to a stay-rope tightener together with a turnbuckle therefor.

Hitherto stay-ropes for electric poles, and the like were generally tightened by aid of turnbuckles inserted into the said ropes, and having at their ends eye-bolts with right and left hand threads.

This method of tightening stay-ropes, however, has the disadvantage that the threaded eye-bolts have to bear the tension in the stay-rope permanently. Furthermore the threads are subject to rust and thereby, in case of emergency, render the turning of the screw difficult or even impossible.

It is the object of the present invention, on the one hand, to avoid these drawbacks, and, on the other hand, to render the construction of such stay-ropes cheaper, by obviating the necessity of having a tightening device in each single stay-rope.

The stay-rope tightener according to the present invention is characterized essentially by two hooked members which may be coupled by the aid of a perforated link in such positions, that the desired tightness will be obtained.

Such tightening is preferably performed by means of a special appliance, a turnbuckle.

In the accompanying drawing a constructional form of the present invention is shown by way of example. In this drawing

Fig. 1 shows in front view the tightener, hooked into the outermost holes of the coupling link.

Fig. 2 is the same in side elevation, together with the turnbuckle engaged in the hooked members.

According to this drawing the stay-rope 50 1 is, at a suitable place, interrupted for a certain distance. To each of the ends of the rope is attached a hooked member 2 and 3, respectively, which are coupled to each other by means of a perforated link 4.

The tightener thus described is employed in such a manner that the hooked members 2, 3 are engaged in such holes in the coupling link 4, that the stay-rope will have the proper tightness.

For thus engaging the hooked members 2 and 3, preferably a special turnbuckle, see Fig. 2, is employed, which acts on quite the same principle as those heretofore known.

This turnbuckle is of that kind which consists of a screw spindle having right and left-hand threads at its ends, on each of which threaded ends is fitted a nut with a hook attached to it.

According to the invention these nuts cannot turn relatively to each other when the screw-spindle is turned.

This is rendered possible, in a special constructional form thereof, by the nuts being positively guided by the hooks attached to them travelling to and fro in slots in a guide-bar.

As said before, the screw-spindle of the turnbuckle has at its one end a right-hand thread and at its other end a left-hand thread. On the threads of the spindle 5 are screwed the nuts 6 and 7 with the hooks 8 and 9, respectively.

The spindle 5 may be turned by means of a swivel-lever 10, and during such turning movement the hooks 8 and 9 are guided in slots in a guide-bar 11.

This guide-bar 11 is provided with an arm 12, rigidly attached thereto, by means of which the turnbuckle can be held while its screw-spindle is being turned.

The turnbuckle described is employed in the following manner: The hooks 8 and 9 are engaged in eyes 13, 14, respectively, in the hooked members 2 and 3, whereupon the coupling-link 4 is put out of tension by turning the spindle 5 by means of the lever 10.

The turnbuckle may also be employed for disengaging the coupling between the hooked members 2 and 3 as, owing to the hooks 8, 9 having a special shape with a nose 15, it is impossible to remove the coupling link 4 without its being put out of tension.

The said coupling link 4 may be made of various lengths, so that, when the stay-rope is tightened the first time, a long coupling link is employed having a suitable number of holes so that it may be used for as many

2
subsequent tightening operations as possible, whereupon this long link is either cut short, or is replaced by a shorter one which is likewise provided with a suitable number of holes.

The invention shall not be limited to the constructional forms shown in the drawing, as the details of these may be varied in many ways without departing from the 10 principle of the invention.

I claim:

1. A stay-rope tightener comprising a pair of hooked members each having an eye at one end and a hook at the other end; 15 and a coupling link provided with a plurality of perforations adapted to engage the hooked members at suitable perforations.

2. A stay-rope tightener comprising a pair of hooked members each having an elongated eye-shaped hole at one end, and a hook at the other end; and a coupling link provided with a plurality of perforations adapted to engage the hooked members at suitable perforations, said hooked members 25 being adapted by means of said eye-shaped holes to be drawn toward each other so that said hooks will engage other perforations of the coupling link.

3. In combination with a stay-rope tightener consisting of two hooked members attached to the ends of the stay-rope and a coupling-link having a plurality of holes, in which said hooked members engage, a turnbuckle consisting of a screw-spindle with, 30 at its ends, right- and left-hand threads, respectively, nuts screwed on said threads, said nuts having hooks adapted to engage in said hooked members of the tightener.

4. In combination with a stay-rope tightener consisting of two hooked members attached to the ends of the stay-rope and a coupling-link having a plurality of holes, in which said hooked members engage, a turnbuckle 40 consisting of a screw-spindle with, at its ends, right- and left-hand threads, re-

spectively, nuts screwed on said threads, said nuts having hooks adapted to engage in said hooked members of the tightener, a guide-bar having slots, said hooks moving in said slots of the guide bar.

5. In combination with a stay-rope tightener consisting of two hooked members attached to the ends of the stay-rope and a coupling-link having a plurality of holes, in which said hooked members engage, a turnbuckle 50 consisting of a screw-spindle with, at its ends, right- and left-hand threads, respectively, nuts screwed on said threads, said nuts having hooks adapted to engage in said hooked members of the tightener, a guide-bar having slots, said hooks moving in said slots of the guide-bar and a handle rigidly attached to said guide-bar.

6. A turnbuckle comprising a screw-threaded spindle; a pair of hooked nuts on said spindle; a guide bar secured at each end to said spindle, and having an arm intermediate of its ends, said guide bar being adapted to prevent said nuts from rotating with said spindle; and means comprising a 60 lever for rotating said spindle.

7. A turnbuckle comprising a screw-threaded spindle; a pair of hooked nuts on said spindle; a guide bar for said nuts secured at each end to the respective ends of said spindle, and having an arm integral with and intermediate of the ends of said bar; and a lever on the end of said spindle 70 for rotating said spindle relative to said nuts.

8. In combination with a stay-rope tightener having hooked members and a connecting link; a turnbuckle comprising a screw-threaded spindle, nuts on said spindle adapted to cooperate with said hooked member, a guide bar and arm for said nuts secured to said spindle, and a lever for said spindle.

In testimony whereof I affix my signature.

SVEND FÆRCH.
